GOLF CLUB AND ATTACHMENT THEREFOR

John W. Buttikofer, New Rochelle, N. Y.

Application January 11, 1940, Serial No. 313,356

3 Claims. (Cl. 273—77)

The present invention relates to means adapted to be used for marking the position of a golf ball, particularly in instances on a putting green where the ball of one player blocks or disturbs the play of a ball of another player.

In playing golf it frequently happens that the ball of one player lies in the path along which another player desires to hit his ball. This occurs most frequently on putting greens where each player of a group endeavors, in succession, to hit his ball into the same cup or hole. All the balls thus tend to congregate about the cup, one or more of them may lie between the cup and the ball of another player. In such cases the ball which lies in the way is usually lifted and its approximate position marked either by roughing up the grass with a finger or by placing a coin or other object on the spot. The first method is generally only an approximation and the second often requires a search through one's pockets for a suitable coin or other object. In many instances players object to other balls on the green while putting, in which case the several players mark their positions.

The present invention aims to provide a simple, inexpensive and practical means for securing and retaining a suitable marking member in readily available position on a golf club. The invention also contemplates the provision of such means which may either be incorporated with a golf club shaft during the manufacture thereof or which may be attached to present golf clubs.

An object of the present invention is to provide means for securing a marking member to a golf club.

Another object of the invention is to provide an inexpensive means for retaining a marking member, which may be readily manufactured.

Another object of the invention is to provide means for retaining a marking member so that it is immediately available for use at all times.

Another object of the invention is to provide a holding means which may be readily incorporated in a golf club during manufacture thereof.

A further object of the invention is to provide means for retaining a marking member which may be readily assembled with existing golf clubs.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has

been chosen for purposes of illustration and description and is shown in the accompanying drawing, forming a part of the specification, wherein

5 Fig. 1 is a perspective view showing a preferred embodiment of the invention at the end of a golf club;

Fig. 2 is an enlarged top plan view of the device illustrated in Fig. 1;

10 Fig. 3 is an enlarged fragmentary elevational view of the device shown in Figs. 1 and 2;

Fig. 4 is a sectional view taken along line 4—4 of Fig. 2;

Fig. 5 is a sectional view of the device illustrated in Figs. 1 to 4 embodied in a separate attachment;

Fig. 6 is a top plan view of a modified form of the invention;

Fig. 7 is a sectional view taken along line 7—7 of Fig. 6;

Fig. 8 is a sectional view taken along line 8—8 of Fig. 7;

Fig. 9 is a side elevational view of another embodiment of the invention;

Fig. 10 is a longitudinal sectional view of the device shown in Fig. 9; and

Fig. 11 is a sectional view taken along line 11—11 of Fig. 9.

Referring again to the drawing and more particularly to Fig. 1 thereof, there is shown a golf club having a head 1, a shaft 2 with a wound grip 4, and a preferred embodiment of the marker retaining means 5 at the upper end of the shaft.

The majority of golf clubs manufactured and sold at the present time are of the tapered, hollow steel shaft variety and Figs. 2 to 4 show the present device embodied in that type of club shaft. In the preferred embodiment the marker retaining device is adapted to hold a flat, relatively thin marker in a suitably shaped recess.

40 A plug 7 made of wood, plastic molding compound or other suitable material is preferably fitted into the hollow club shaft 8 so as to frictionally engage the inside of the shaft. If desired, a bolt or screw may extend through a side of the shaft and into the plug 7 to hold it in position. The plug 7 has an upwardly facing recess 10 at the upper part thereof which contains a spring 11 for supporting and urging outwardly a ball member 13.

Excessive upward movement of the ball 13 is prevented by an apertured plate 14 secured to the plug 7 by screws 16 or by other suitable means. The aperture 17 in the plate is slightly smaller than the diameter of the ball 13 to allow part of the ball to project outwardly through the

plate 14 but to prevent the ball 13 and spring 11 from separating from the plug 7.

After the plug 7 with the ball and spring assembly has been inserted into the club shaft 8, the upper end of the steel shaft is turned over to form an inwardly extending flange 18 spaced slightly above the ball 13 and plate 14 of the internally fitted plug assembly. A recess 19 is thus formed between the plug plate 14 and the flange 18 of a size adapted to receive a marker 20.

The marker 20 preferably comprises a relatively thin, flat member, preferably disc-like, which is pressed against the inwardly extending flange 18 at the upper end of the club shaft by the resilient cooperating ball and spring construction. The term "disc-like" is intended to apply equally as well to circular, oval, square or other shapes of markers. To facilitate insertion into and removal from the recess 19 of the marker 20, the flange 18 on the club shaft is preferably cut away at one side thereof (Fig. 2). This construction allows the marker 20 to be easily inserted from a sidewise direction under the flange 18 or to be removed in a sidewise direction from beneath the flange 18. The ball is pressed upwardly by the spring 11 at all times to hold the disc member 20 firmly against the underside of the inwardly extending flange 18.

When it is desired to mark the position of a player's ball the marker 20 may be easily removed from the recess 19 of the holder by pressing it downwardly and outwardly through the open portion of the flange. To place the marker back in the holder the reverse procedure may be easily followed.

The marker may have, if desired, a recess or depression 21 as shown in Fig. 5 at each side thereof for receiving the ball member 13; this forms a resilient locking arrangement which minimizes any possibility of accidentally dislodging the marker.

In Fig. 5 the preferred embodiment of the invention is shown included in an attachment for a golf club rather than actually built into a club. A marker retaining member 22 is provided with a recess 23 at its lower part adapted to fit over the end of a club handle and be secured thereto by a screw or bolt (not shown) extending through a hole 24 therein. While this retaining member 23 is shown with a recess or aperture 23 so that it may fit over a club shaft, it will be clear that a plug-type end could be provided instead so that it could fit into the end of a hollow shaft. An inwardly extending flange 18a is provided adjacent the upper end of the retaining member 22 similar to that described in connection with Figs. 1 to 4 and this flange 18a is cut away in a similar manner at one side thereof to facilitate insertion and removal of a marker 20a. A recess 10a at the upper part of the retaining device carries a spring 11a and ball member 13a and the upper end of this recess 10a is buried over to prevent accidental separation of the ball 13a from the recess. During insertion or removal of the marker 20a, the attachment operates in the same manner as the previously described device which is built into a golf club.

Another form of the attachment type of retaining device and marker is shown in Figs. 6 to 8. A cup-shaped or suitably recessed member 25 is adapted to fit over the end of a golf club and be attached thereto by a screw or bolt (not shown) passing through a hole 26 at the side of the recessed member. An aperture 28 through the top of the recessed member 25 is adapted to

receive a marker member 33 to be later described. Instead of fitting over the end of a shaft, the recess member 25 may have a projection (not shown) adapted to fit into the end of a hollow shaft.

5 A substantially flat, circular type of spring 29 adapted to cooperate with a modified form of marker 33 is located in the recessed member 25 adjacent the upper part thereof and has outwardly expandible portions or legs 31 and 32 adjacent its center part for cooperating with the modified form of marker 33. The flat spring 29 is maintained in position by an apertured plate 34 fitted within the recessed member 25 and held in position adjacent the upper part thereof by means of a screw or bolt 35 which extends through the side wall of the recessed member 25. The apertured plate 34 need not firmly grip the spring 29 in position against the upper end of the recessed member, for excessive lateral movement of the spring 29 is limited by the side walls of the recessed member 25.

10 The marker 33 which cooperates with the above described retaining device preferably comprises a relatively thin, flat, disc-like portion 36 with a pointed, outwardly projecting part or shank 37 secured to one side thereof. The projecting shank 37 fits, in assembled position, within the aperture 28 of the recessed member 25, the aperture of the plate member 34 and between the resilient legs 31 and 32 of the flat spring member 29. The resilient spring legs 31 and 32 contact the sides of the projecting shank 37 and retain the marker 33 to the device. The projecting shank 37 may have a groove or channel 38 therein to receive the resilient spring legs 31 and 32 so as to more securely hold the parts together. The marker 33 may be removed from the holder by pulling it upwardly, whereupon the resilient spring legs 31 and 32 will yield outwardly. In use the pointed shank 38' of the marker 33 may be pushed into the ground, leaving the flat disc-like portion 36 visible to indicate the original position of a golf ball.

15 In Figs. 9 to 11 there is illustrated a further modified form of the invention adapted to retain a flat, relatively thin marker 20b of the type described in connection with the preferred embodiment. An outer casing member 39, which carries the means for retaining the marker, is provided with a recessed lower portion to receive the end of a golf club shaft and be secured thereto by a screw or bolt (not shown) which passes through an aperture 40 at one side of the casing member 39. Where the device is to be attached to a golf club having a hollow shaft, a projection of reduced diameter may be attached to the device and fitted into the hollow end of the club shaft.

20 The means for normally retaining a marker within the device in this instance preferably comprises a pair of suitably curved resilient members 41 and 42 screwed, riveted or otherwise attached in spaced relation at one end thereof to the inside of, and adjacent the upper portion of, the walls of the recessed outer casing member 39. The free ends 43 and 44 of the spaced resilient members press toward each other against the periphery of the marker 20b to hold it in position within the device. The marker 20b may be inserted into and removed from the device by passing it through a recess 45 provided through the side wall of the casing member 39 substantially in line with the curved, resilient marker retaining members 41 and 42. A lower plate 46 fitted 25 within the casing 39 below the curved resilient

members 41 and 42 maintained in position by a screw or bolt 47 holds a marker 20b up between these members and in line with the side wall recess 45.

The marker 20b may be removed from the device by means of a lever 48 pivotally mounted on the lower plate 46 and operable through a recess 49 located in the wall of the casing 39 intermediate the secured ends of the resilient marker holding members 41 and 42. This lever 48 has one end projecting slightly out of the casing 39 at all times so that it may be moved circumferentially with a finger, thus causing the opposite inner end to press against the marker 20b and eject it through the opposite aperture 45. It will be seen that the present invention provides a simple and inexpensive device adapted to be utilized with a golf club for retaining a marking member in immediately available position at all times. The device may be incorporated with a golf club during manufacture thereof or may be made as an attachment for existing golf clubs. In addition the device is rugged in construction and well able to withstand the rough usage which it may be expected to receive.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a device of the class described, the combination of a member having inturned flange portions at its upper end, a rigid fixed surface spaced slightly from said flange closing the space below the flange to form a seat for a disc marker and to assure sufficient space below the flange portion to permit easy insertion and removal of the marker, said flange being recessed for a part of its periphery, said recess extending down to

said fixed surface to permit a disc to be inserted into and removed from said seat, a cavity in said surface, a ball in said cavity and resilient means in the cavity beneath the ball to urge the ball upwardly against a marker on said surface to resiliently hold said marker in place, said ball being adapted to rotate to facilitate insertion and removal of the marker.

2. In a device of the class described, in combination, a golf club shaft having a hollow portion and an inwardly extending flange adjacent the upper part thereof, a plug located within the hollow portion of said shaft and spaced from said inwardly extending flange so as to form a seat adapted to receive a marker, said plug having a recess therein for containing marker retaining means seated at the lower part of said recess, a marker contacting member normally urged upwardly by said resilient means against a marker so as to retain the marker on its seat, and an apertured plate attached to said plug over the recess therein to retain said marker contacting member in position within the plug recess.

3. In a device of the class described, the combination of a substantially cylindrical member for attachment to the end of a golf club, a recess on the side of said member at the upper end thereof, grooves extending in a plane substantially perpendicular to the axis of the member leading to said recess and adapted to receive the edges of a marker, said member having a rigid part below the grooves bridging the space therebetween to assure sufficient space for insertion and removal of the marker, said rigid part having a cavity with its open end adjacent the plane of the lower side of said grooves, a ball free to rotate in said cavity to facilitate insertion and removal of a marker, and resilient means at the bottom of said cavity for urging said ball against a marker seated in said grooves.

JOHN W. BUTTIKOFER.
